CHARM PENDANT

Janetta Friedrich, 41 Meadow Lane, Laurel, Md.

Filed June 7, 1962, Ser. No. 70,454

Term of patent 14 years

(Cl. D45—17)

FIG. 2.

FIGURE 1 is a front elevational view of a charm pendant showing my new design, the opposite side thereof being substantially a mirror image of the side shown.

I claim:

The ornamental design for a charm pendant, as shown and described.
